UNITED STATES PATENT OFFICE.

LOUIS C. BENNER, OF TOLEDO, OHIO.

BURNER.

1,372,265.

Specification of Letters Patent. Patented Mar. 22, 1921.

Application filed July 26, 1920. Serial No. 398,891.

To all whom it may concern:

Be it known that I, LOUIS C. BENNER, a citizen of the United States, residing at Toledo, in the county of Lucas and State of Ohio, have invented certain new and useful Improvements in Burners; and I do declare the following to be a full, clear, and exact description of the invention, such as will enable others skilled in the art to which it appertains to make and use the same.

This invention relates to an improved burner, for use in connection with a stove or heater of the type disclosed in my prior Patent No. 1288807 issued December 24, 1918, and one object of the invention is to provide a burner which may be formed in two sections releasably connected so that the sections of the burner may be taken apart when it is desired to clean the burner. Another object of the invention is to so construct the burner that the kerosene or other liquid fuel will enter the burner at the outer end of a nozzle forming a portion of the same and will pass through passages upon opposite sides of the nozzle to an outlet valve thus permitting the liquid fuel to be readily converted into a gas before entering the valve housing.

Another object of the invention is to so construct the burner that the nozzle thereof will be provided with a relatively wide and flat outlet having a baffle positioned therein to divide the flame and cause the flame to pass out of the nozzle in a wide and flat flame.

Another object of the invention is to so construct this burner that the two sections will interlock and thus be braced against longitudinal or transverse movement when the two sections are put together and secured.

Another object of the invention is to so construct the burner that the same may be formed in two parts formed by a single casting and thus provide a burner which can be cheaply produced and which will be strong and durable and very efficient in operation.

This invention is illustrated in the accompanying drawings, wherein:

Figure 1 is a view in elevation showing a heater having the improved burner associated therewith.

Fig. 2 is an enlarged side elevation of the assembled burner.

Fig. 3 is a side elevation showing the sections of the burner separated.

Fig. 4 is an end elevation of the assembled burner.

Fig. 5 is an end elevation showing the sections of the burner separated.

Fig. 6 is a longitudinal sectional view taken along the line 6—6 of Fig. 2.

Fig. 7 is a longitudinal sectional view taken along the line 7—7 of Fig. 4.

Fig. 8 is a transverse sectional view taken along the line 8—8 of Fig. 7.

This burner is used in connection with a heater of the type disclosed in my previous patent referred to above and including briefly a fuel tank 1 carried by a supporting frame 2 which frame extends above the fuel tank and carries the compartment 3 in which the soldering iron or other tools which are to be heated will be placed. A filling neck 4 is provided for the fuel tank 1 and an air pump 5 is provided so that the necessary air compression may be supplied to force the liquid fuel through the outlet pipe 6. The burner which is indicated in general by the numeral 7 in Fig. 1 is positioned as shown in Fig. 1 so that the flames will be directed longitudinally through the compartment 3 and this burner is positioned above the pan 8 into which a supply of fuel will be poured when first starting the heater. This burner is of the retort type and it is, of course, obvious that the burner must be heated in order to permit the liquid fuel to be converted into gas. Therefore, when first starting the furnace, the pan will be filled with fuel which will be ignited and this fuel will serve to heat the burner so that when the valve 9 is opened to permit kerosene or other liquid fuel to flow through the pipe 6 and into the burner through the neck 10, the fuel will be converted into gas.

This burner is formed in two sections, the upper section being indicated by the numeral 11 in Fig. 2 and the lower section by the numeral 12. The lower section is formed in a single casting and is provided with an end wall 13 and side walls 14 which extend parallel from the end wall to a point approximately midway the length of the lower section and are then extended in flaring relation. The end wall is cut out to provide a pocket 15 having a reduced lower end portion or auxiliary pocket 16 and one side wall 14 is cut adjacent the rear wall 110.

to provide a pocket 17 which communicates with the pocket 15 at one side thereof. Notches 18 are formed in the rear end portions of the side walls adjacent the end wall 13 so that the pan 8 may fit into these notches and thus assist in supporting the burner when put in place as shown in Fig. 1. A nozzle section is cast integral with the side walls and is positioned between the 10 same and provided with a flat and flaring forward or outlet end portion 19 and a trough-shaped rear end portion 20 having notches 21 formed in its upper edge for a purpose to be hereinafter brought out. A 15 post 22 is positioned in the central portion of the flared end portion 19 of this nozzle section and serves to divide the sheet of flame passing through the nozzle as will be hereinafter brought out. It should be noted 20 that the nozzle extends beyond the forward ends of the walls as shown in Fig. 3.

The upper section is in the form of a flat plate 23 which rests upon the lower section and has ribs 24 cast integral therewith and 25 extending longitudinally of its under face as shown in Fig. 8. A valve housing 25 is also cast integral with the plate 23 between the ribs 24 and is provided with a rearwardly extending neck 26. This valve housing and 30 the rear end portions of the ribs 24 will fit into the cutout 15 and reduced lower end portion 16 thereof, and a side arm 27 leading from one of the ribs 24 will fit into the cutout 17. Webs 28 are carried by the ribs 35 24 and provided with flaring forward end portions 29, the webs engaging the upper edges of the nozzle section of the lower burner section and together therewith forming a nozzle having a tubular rear end portion and a flaring outlet end. It should be noted that the plate 23 is thickened between 40 the flaring outer end portions 29 of the webs 28 and that the webs are provided with notches 30 which coöperate with the notches 45 21 and thus form side openings in the nozzle so that air may enter the nozzle through these side openings as well as through the open rear end portion of the nozzle and thus sufficient air supplied to properly 50 mix with the gas and form a good mixture. It should be further noted that the webs 28 are provided with depending lugs 31 for engaging the sides of the lower nozzle section and thus preventing the two 55 nozzle sections from moving transversely. The forward ends of the side walls 14 engage the flaring end portions 29 of the webs 28 to assist in preventing the two sections from having longitudinal movement and the 60 side arm 32 which extends from the forward end portion of the upper section is provided with a depending lip 33 for engaging the extended forward end portion of the lower nozzle section as shown in Fig. 4. It will 65 thus be seen that the two sections interlock,

and therefore, when the securing screws 34 are passed through the openings 35 of the side walls 12 and screwed into the threaded openings 36 of the webs 28, the upper and lower sections of the burner will be securely 70 connected and cannot have independent movement and further will be prevented from having any tendency toward warping when they are heated and cool off.

The thickened forward end portion of the 75 upper section is provided with a transversely extending fuel inlet passage 37 which has its end portion closed by the screws 38 which constitute plugs to prevent the escape of the liquid fuel through the ends of the passage. 80 At one end, the passage 37 communicates with an opening 39 formed in the side arms 32 so that liquid fuel from the pipe 6 may pass through the elbow 10 and up through the passage 39 into the passage 37. Branch 85 passages 40 extend from the passage 37 upon opposite sides of the burner and have their rear ends closed by the screw plugs 41. A side passage 42 is formed adjacent the rear end of the upper section and has its outer 90 end closed by the screw plugs 43. It will thus be seen that the fuel which passes through the passages 40 will pass through the side passages 42 and into the valve housing through the passage 44. This passage 44 is 95 closed at its lower end by the plug 45 and intersects a passage 46 formed longitudinally of the valve housing and having its walls threaded for a portion of its length for engagement by the threads of the valve 100 stem 47. This stem 47 extends through the neck 26 and carries a hand wheel 48 so that the valve stem can be easily rotated. The valve stem is tapered at its forward end to provide a needle valve 49 which extends 105 through the pit 50.

When this burner is in use, the pipe 6 is connected with the elbow 10 which in its turn is connected with the side arms 32 of the upper section. A supply of fuel is 110 placed in the pan 8 and lighted and after the burner has been preheated by the fuel placed in the pan, the valve 47 will be opened and the fuel will flow through the burner. As the fuel enters the burner it passes 115 through the passage 37 and then will pass through the passages 40. In doing so, the fuel will be converted into a gas by the heat, and therefore, when the fuel passes into the valve housing, it will be in a gaseous form instead of in a liquid form. This gas will pass out through the outlet pit 50 and will be ignited. The jet of flame which will be under compression due to the presence of compressed air in the reservoir 1, will pass 120 through the nozzle of the burner and upon reaching the wide and relatively flat outlet end portion of the burner, it will be divided by the post 22 and will pass out of the burner in a flat and relatively wide sheet 125 130

of flame. Therefore, the soldering iron or other tools which are placed in the compartment 3 will be subjected to the action of a wide and flat flame which is very hot and will be quickly heated. There has thus been provided a burner which is very efficient in operation since the liquid fuel passes into the burner across the wide inlet end portion of the nozzle and then divides and passes longitudinally of the burner upon opposite sides of the nozzle before reaching the valve housing. The construction of the burner causes the two sections to be securely but releasably held in engagement with each other and prevents them from being warped. The construction further permits the burner to be easily taken apart and cleaned when necessary.

I claim:

20 1. A burner comprising a housing having a lower section including side walls and an end wall cut to provide a recess, an upper section forming an upper wall for the housing having a valve housing carried thereby and seated in the recess of the lower section and extending longitudinally of the housing, a lip carried by the side walls of the housing and having a reduced extension forming a trough extending inwardly between the side walls, longitudinally and transversely extending ribs cast upon the upper wall, the transverse rib having an inlet passage formed therein and the longitudinal ribs having passages leading from the inlet passage and communicating with the valve housing, webs formed upon the ribs and contacting with the lip and trough extension to provide a nozzle positioned in front of the valve housing and having air inlet openings in its sides, and valve means controlling the passage of fluid out of the valve housing.

25 2. A burner comprising a housing open at its forward end and bottom and having a lower section constituting side walls and a rear end wall and an upper section constituting an upper wall, a lip cast integral with and extending between and forward of the side walls and having a rearwardly extending trough extension between the side walls, webs cast upon the upper wall and engaging the trough and side portions of the lip and forming therewith a nozzle, a valve housing cast upon the upper wall for directing fluid into the rear end of the nozzle, and the upper wall having a transversely extending inlet passage adjacent its forward end and branch passages extending longitudinally of the upper wall from the inlet passage adjacent the ribs and communicating with the valve housing through the sides thereof.

30 3. A burner comprising a housing, an upper wall, side walls and a rear end wall, a valve housing carried by the upper wall adjacent the end wall, a nozzle positioned between the side walls tapering inwardly and

terminating adjacent the valve housing and open at its inner end and having side openings, the upper wall having a fluid inlet passage extending transversely of the nozzle adjacent the outer end thereof and passages 70 extending longitudinally of the housing upon opposite sides of the nozzle and having side passages communicating with the valve housing.

4. A burner comprising a housing having 75 a lower section constituting side walls and a rear end wall and an upper section constituting an upper wall, a nozzle positioned between the side walls and formed in sections integral with the sections of the housing 80 and extending rearwardly of the housing and open at its inner end, a valve housing carried by the upper wall to the rear of the open inner end of the nozzle, the upper wall having a fluid inlet passage extending transversely of the nozzle adjacent the outer end thereof and passages extending longitudinally of the housing upon opposite sides of the nozzle and having side passages communicating with the valve housing. 90

5. A burner comprising a housing having a lower section and a removable upper section, a valve housing carried by the upper section, a nozzle having upper and lower sections carried respectively by the sections of 95 the housing, the upper section of the housing having a transversely extending fluid inlet passage adjacent the forward end of the nozzle and longitudinally extending passages leading from the inlet passage upon 100 opposite sides of the nozzle and communicating with the valve housing.

6. A burner comprising a housing having a lower section and an upper section, the upper section fitting into the lower section 105 and having portions fitting into pockets formed in the walls of the lower section whereby the sections will interlock and be held against independent movement, a nozzle having upper and lower sections carried respectively by the sections of the housing and having their edges contacting, and a valve housing carried by the upper housing section, the upper housing section having fluid passages formed therein communicating with the valve housing. 115

7. A burner comprising a housing having upper and lower sections, the lower section having walls cut to receive portions of the upper section and retain the sections against 120 independent movement, a nozzle extending longitudinally of the housing and having sections carried by the housing sections, and a valve housing carried by the upper section and fitting into a cutout of the lower section 125 and positioned in operative relation to the nozzle, the upper section being provided with fluid passages communicating with the valve housing.

8. A burner comprising a housing having 130

an upper section and a lower section, the lower section including an end wall, side walls and a nozzle section secured between the side walls and extending beyond the forward ends thereof, the end wall and one side wall being provided with communicating cutouts, the upper section resting upon the lower section and extending beyond the forward ends of the side walls thereof and having a valve housing and nozzle section formed integral and extending between the side walls of the lower section and resting upon the nozzle section thereof, the forward end portion of the upper nozzle section engaging the forward ends of the side walls

and having a transversely extending fluid passage, the valve housing and rear end portion of the upper section fitting into the cutouts of the rear wall and side wall and the upper section being provided with branch 20 passages leading from said fluid passage and communicating with the valve housing.

In testimony whereof I have hereunto set my hand in the presence of two subscribing witnesses.

LOUIS C. BENNER.
